Wilson W. Howard

UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DEVICE FOR APPLYING FLUIDS TO SHOES.

1,274,407.

Specification of Letters Patent. Patented Aug. 6, 1918.

Application filed February 11, 1916. Serial No. 77,754.

To all whom it may concern:

Be it known that I, FREDERICK M. FURBER, a citizen of the United States, residing at Revere, in the county of Suffolk 5 and State of Massachusetts, have invented certain Improvements in Devices for Applying Fluids to Shoes, of which the following description, in connection with the accompanying drawings, is a specification, like 10 reference characters on the drawings indicating like parts in the several figures.

This invention relates to devices for use in applying to articles such as boots and shoes, in the process of their manufacture, 15 relatively thick fluids such as enamel or cement, and is herein shown as embodied in fluid dispensing mechanism particularly adapted for use in machines for repairing imperfections in the surface of patent or 20 enameled leather, such as the machine described in my prior Patent No. 1,096,423, granted May 12, 1914. It should be understood, however, that although the invention 25 is of particular utility in a machine of this character, it is not thus limited in its applicability, but is susceptible of a variety of uses other than those herein specifically mentioned.

An important object of the invention is to 30 provide, in a device for dispensing relatively thick fluids such as patent leather repairing enamel, means for increasing above normal the tendency of the fluid to flow from the receptacle through the delivery outlet whenever 35 the outlet valve is opened, in order that the required quantity of the fluid may be obtained at any time without undue delay. To this end, a feature of the invention consists in means of novel and improved construction for effecting a constant accumulation 40 of fluid under pressure in the outlet portion of the receptacle, without, however, developing undue pressure when the outlet is closed. In the construction herein shown 45 a cylindrical member is mounted for rotation within the receptacle in such manner as to carry toward the outlet the fluid that adheres to its periphery, and a deflector is arranged at one side of the outlet to re-

move or divert from the rotatable member 50 the fluid that adheres to or is entrained thereby and cause this fluid to accumulate at the outlet. In this illustrative construction, moreover, the cylindrical member is so arranged relatively to the walls of the 55 receptacle as to facilitate the development of pressure on the fluid in the outlet portion of the receptacle, affording, however, sufficient provision for escape of the fluid to avoid the development of undue pressure when the 60 outlet is closed.

For some kinds of work it is necessary or desirable to have at hand, ready for convenient use, fluids of different kinds or of different consistencies. In shoe repair work, 65 for example, shoes with plain toes, in which the toe portion of the leather is relatively flexible, require for durability a thicker enamel than do the relatively inflexible box toes. It is accordingly a further object of 70 the invention to provide improved fluid dispensing means such as to enable the operator to use different fluids at will; and to this end a further feature of the invention consists in means for rendering different fluids constantly available for use under an increased 75 outlet pressure without the danger of developing an undesirable pressure in any receptacle the outlet from which is closed.

Still another feature of the invention consists in the combination of a plurality of receptacles adapted to contain different kinds of fluid and each provided with an outlet, and means affording a single delivery passage or nozzle arranged to communicate 80 selectively with the outlets of the different receptacles and having a delivery valve constructed to be opened by engagement with the work to which fluid is to be applied, thus affording the operator a choice of different fluids, while delivering the fluid at the precise point desired with reference to other portions of the machine and permitting unobstructed manipulation of the work presented to the nozzle.

The above and other features and objects of the invention, including certain details of construction and combinations of parts, will

now be described with reference to the accompanying drawings and pointed out in the claims.

In the drawings:

5 Figure 1 is a perspective view of mechanism in which the invention is embodied, with portions broken away in order to illustrate more clearly the interior construction, this view illustrating the relation of the 10 mechanism to other portions of a machine such as that shown in my patent hereinbefore referred to,

Fig. 2 is a side elevation, partly in section, of a portion of the mechanism shown 15 in Fig. 1,

Fig. 3 is a section on the line 3—3 of Fig. 2, and

Fig. 4 is a view of the outlet nozzle and parts associated therewith.

20 The device includes a casting 2 which may be supported upon the machine in any suitable manner not illustrated herein in detail, this casting being chambered to provide two fluid receptacles 4 and 6 separated by a partition 8, and having ledges 10 to support in inverted position bottles *a* and *b* containing fluid enamel of different kinds or consistencies. The enamel is thus permitted to drain from the bottles into the respective 25 receptacles and to be held in the receptacles without undue exposure to the air. A cover 12 fits over a rim 14 on the casting 2 and is secured in position by means of a set screw 16, thus further protecting the enamel 30 supply.

Bolted to the member 2 is a casting 18 which serves as a front closure for the receptacles 4 and 6 and is provided with outlet passages 20 and 22 leading from the respective receptacles and communicating with a common delivery opening or passage 24. Valves 26 and 28 control the respective outlets 20 and 22 so that either outlet may be closed or opened irrespective of the other. 45 The opening 24, in the construction shown, is adapted to receive the tapered end 30 of the nozzle member 32 having a delivery passage 34 controlled by a gate valve 36 pivoted at 38 and normally held closed by a 50 spring 40. The novel features of construction of the nozzle member and the valve are not claimed herein, since they form the subject matter of another application Serial No. 750,303, filed Feb. 24, 1913. In the construction herein shown a valve 42 also is provided to control further the flow of fluid through the passage 34.

60 Mounted in bearings in the casting 2 and extending through the receptacles 4 and 6 is a shaft 44 upon which are mounted in the respective receptacles cylindrical members 46 which may be formed as hollow drums or may have any other convenient or suitable construction. These members turn with 65 their ends in close relation to the side walls

of the receptacles and are of such diameter as to provide between their peripheral surfaces and the walls of the receptacles considerable spaces for the reception of the fluid. The shaft 44 may be driven in any 70 suitable manner from other operative portions of the machine, so as to turn the members 46 in the direction indicated by the arrow in Fig. 2.

Opposite to the outlets 20 and 22 in the 75 respective receptacles 4 and 6 are deflectors 48, each of which substantially closes the passage between the periphery of the member 46 and the wall of the respective receptacle, and is arranged to engage or to extend into very close relation to the peripheral surface of the member 46. These deflectors, in the construction shown, are conveniently formed as part of the casting 80 18. As the member 46 is turned in the direction of the arrow, the deflector 48 thus serves to remove or divert from the periphery of the member the fluid that adheres thereto, or is entrained thereby, and causes this fluid to accumulate adjacent to 85 the outlet under a pressure which is greater than normal by reason of the constant accession of fresh quantities of the fluid in the outlet portion of the receptacle and the frictional drag upon the fluid in the direction of the outlet occasioned by the rotation 90 of the member 46. In order to facilitate the development of pressure in the outlet portion of the receptacle, the member 46 is mounted with its periphery in close relation 95 to the wall of the receptacle on the opposite side of the outlet from the deflector 48, thus nearly isolating from the remainder of the receptacle that portion which is adjacent to the outlet. The narrow passage 50, 100 however, between the member 46 and the wall of the receptacle affords sufficient relief to prevent the development of an undesirable degree of pressure in the outlet portion of the receptacle when the outlet is 105 closed.

In the use of the device, suitable supplies of fluid, such as enamel of the required kinds or consistencies, are maintained in the respective receptacles 4 and 6, and the valves 115 26 and 28 are set to open one of the outlets 20 or 22 and close the other outlet in accordance with the kind of enamel which it is desired to use. When it is desired to apply the usual small quantity of enamel 120 to the surface to be repaired, the shoe is placed in contact with the valve 36 and the valve lifted in the manner described in my other application hereinbefore referred to. The shaft 44 meanwhile is constantly rotated, and in consequence pressure is maintained in the manner above explained in the outlet portions of both receptacles, which causes the enamel to flow promptly and freely from the nozzle the moment the valve 130

is opened. It will be evident, however, that by reason of the relief passages 50 the pressure at either outlet cannot increase above a certain small maximum irrespective of the 5 opening or closing of the outlets or of the nozzle passage 34. The invention consequently insures, during the operation of the machine, effective and prompt delivery of the required quantity of enamel, and permits the choice of different kinds of enamel 10 with the same insurance of prompt delivery of either kind; and at the same time, no undesirable consequences are involved in the closure of the outlet from a receptacle for 15 the time being not in use.

The construction herein described, comprising a single delivery passage or nozzle arranged to communicate with different fluid receptacles, has an important advantage, 20 particularly in a machine of the type herein referred to in which the delivery of the fluid is controlled by a valve arranged to be opened by engagement with the work. It is essential to the most efficient use of a 25 machine of this character that the fluid be delivered at a point as near as possible to other operating instrumentalities to which the work is to be subsequently presented. If the machine, however, were provided with 30 a separate delivery nozzle for each receptacle, both nozzles could not be located near enough to the desired point to satisfy the above mentioned requirement, since such an arrangement would position the nozzles so 35 near to each other that when the work were pressed against one of the valves to receive the fluid at the point required, the other valve also, unless great care were exercised, would be likely to be engaged and opened 40 by the work, and either nozzle and valve would obstruct the free manipulation of the work presented to the other nozzle. The dispensing device constructed in accordance with a feature of this invention, including 45 a single valve controlled delivery passage or nozzle which may be put in communication with different fluid receptacles, permits the fluid to be delivered at the precise point desired and imposes no restriction upon the 50 free manipulation of the work, while at the same time rendering it possible to use different fluids at will.

Although the invention is disclosed herein as embodied in mechanism having the specific features of construction shown and described, it should be understood that various detailed embodiments are comprehended within the scope of the invention as defined in the claims.

Having described the invention, what I claim as new and desire to secure by Letters Patent of the United States is:

1. A device of the class described comprising, in combination, a fluid receptacle provided with an outlet, a cylindrical member

rotatable in said receptacle with its peripheral surface spaced from the walls of the receptacle and its ends closely adjacent to the sides of the receptacle, and a deflector constructed and arranged to divert from the 70 periphery of said member the fluid entrained thereby, said deflector being constructed to close substantially the passage between the periphery of said member and one of the walls of the receptacle, and the 75 peripheral surface of said member being closely adjacent to another wall of the receptacle to form a restricted fluid passage of such size as to cause the accumulation of fluid under pressure at the outlet. 80

2. A device of the class described comprising, in combination, a fluid receptacle provided with an outlet, a cylindrical member rotatable in said receptacle with its ends closely adjacent to the sides of the receptacle, a deflector substantially closing the passage between the periphery of said member and the walls of the receptacle at one side of the outlet and arranged to divert from said member the fluid entrained thereby, said 85 parts being arranged to provide a restricted passage between said member and the walls of the receptacle at the other side of the outlet of such size as to cause the fluid diverted from said member to accumulate under pressure at the outlet without developing undue pressure when the outlet is closed, and means for controlling the delivery of 90 fluid through the outlet. 95

3. A device of the class described comprising, in combination, a fluid receptacle provided with an outlet, a member arranged for rotation in said receptacle with its ends closely adjacent to the sides of the receptacle and its periphery spaced from the walls 100 of the receptacle to form a passage to convey toward the outlet fluid that adheres to said member, means at one side of the outlet for removing from said member fluid that adheres thereto, said parts being constructed and arranged to provide a restricted passage between said member and the walls of the receptacle at the other side of the outlet of such size as to cause the fluid removed from said member to accumulate 105 under pressure in the vicinity of the outlet without developing undue pressure when the outlet is closed, and means for controlling the delivery of fluid through the outlet. 110

4. A device of the class described comprising, in combination, a fluid receptacle provided with an outlet, a cylindrical member rotatable in said receptacle with its ends closely adjacent to the sides of the receptacle, and a deflector substantially closing the passage between the periphery of said member and the walls of the receptacle at one side of the outlet and arranged to divert from said member the fluid entrained 115 120

125

thereby, said member being arranged with its periphery in such relation to the walls of the receptacle at the other side of the outlet as to provide a restricted passage for 5 fluid of such size as to cause the fluid to accumulate under pressure between said deflector and restricted passage.

5. A device of the class described comprising, in combination, a pair of fluid receptacles each provided with an outlet connected to a common nozzle, means for controlling the delivery of fluid through said outlets to permit either of the outlets to be open while the other is closed, and interconnected constantly rotated driven means in each of the receptacles for causing the fluid to accumulate under pressure at the outlet, said means being constructed and arranged to prevent the development of undue 20 pressure at the outlet in either receptacle when said outlet is closed during the use of fluid from the other receptacle.

6. A device of the class described comprising, in combination, a pair of fluid receptacles each provided with an outlet, 25 means for controlling the delivery of fluid through said outlets to permit either of the outlets to be open while the other is closed, a nozzle provided with a work controlled valve arranged for communication with either of 30 said outlets, a constantly driven member in each receptacle for conveying toward the outlet fluid that adheres to said member, and a deflector in each receptacle for diverting the fluid from the surface of said member to 35 cause the fluid to accumulate under pressure at the outlet, said parts being arranged to prevent the development of undue pressure when the outlet is closed during the use of fluid from the other receptacle. 40

In testimony whereof I have signed my name to this specification.

FREDERICK M. FURBER.
